UNITED STATES PATENT OFFICE.

CHARLES ELISHA FOGG, OF KENNETT SQUARE, PENNSYLVANIA.

INTERNAL-COMBUSTION ENGINE.

973,268.

Specification of Letters Patent. Patented Oct. 18, 1910.

Application filed June 11, 1909. Serial No. 501,465.

To all whom it may concern:

Be it known that I, CHARLES E. Fogg, a citizen of the United States, and a resident of Kennett Square, in the county of Chester 5 and State of Pennsylvania, have invented a certain new and useful Internal-Combustion Engine, of which the following is a full, clear, and exact description.

The principal objects which the present 10 invention has in view are: to provide simple and efficient means for lubricating engines of the character specified and the internally contained piston rod connections; and to provide a construction therefor which 15 is simple, efficient and durable.

One embodiment of the present invention is disclosed in the construction illustrated in the accompanying drawings, wherein like characters of reference indicate like 20 parts throughout the views, and in which—

Figure 1 is a side elevation partly in section, of a multiple arrangement of engines built in conformity with this invention, and mounted in quadrant arrangement upon a 25 driving shaft; Fig. 2 is a vertical section taken on the line 2—2 in Fig. 1.

The present invention is illustrated in the accompanying drawings and herein described as being applied to an engine, the 30 construction whereof most clearly necessitates the needs for the use of a lubricating device of the character described.

The timing mechanism and the carbureting mechanism, employed in conjunction 35 with an engine built in conformity with this invention, do not differ materially from those which are at present in use and, therefore, form no part of the present drawings or specification. It is sufficient to state in 40 this connection, that the mechanism for timing the explosions is such that in each of the assembled elements constituting an engine, the explosions will transpire in the upper and lower ends of the cylinder 6 after 45 the crank pin 7 has passed the center line. The same practice in this connection will be followed, as in internal combustion engines of other makes, wherein by changing the 50 sparking period with reference to the highest compression, the propelling force of the explosion is diminished.

In the present invention the piston 8 is a double-ended and closed cylinder as shown in Fig. 2 of the drawings, and is provided 55 with the usual packing rings 9. The side walls are formed to a sufficient length to

operate as guides within the cylinder 6. At each side of the median line and on opposite sides of the cylinder are introduced exhaust ports 10, 10, and the intake ports 11 and 12. The piston 8 is provided with extensions 13 and 14 disposed in line with the intake ports 11 and 12. The extensions 13 and 14 are provided with curved walls adapted to align with the ports 11 and 12 to divert the inrush from the said ports and compel the flow thereof toward the extreme upper and lower ends of the cylinder 6, according as the said intake is from the port 11 or the port 12, or on the upper or the lower side of the median line.

The piston rod 15 is extended through a suitable housing 16, packed in any suitable manner, the packing being secured in position therein by a gland 17.

The lower end of the piston rod 15 is fixedly secured in the upper surface of the head of a plunger 18 mounted in a cylindrical race 19, which at the upper end widens to the compression chamber 20 and 80 at the lower end to the chamber 21 forming the casing or runway for the crank pin 7, and the crank arms 22 which are rigidly mounted upon a shaft 23. The plunger 18, being connected on the same rod, has the 85 same length of travel. On the median line of the limits of the travel of the plunger 18 there is introduced into the race 19 the inlet tube 24 leading from the carburetor.

It will be observed that the pipe 24 is 90 fully opened only when the plunger 18 is at rest, which is when the crank pin 7 is moving past the center line at the top and bottom of the stroke. At such times the plunger having passed beyond the pipe 24, there 95 has been caused within the race 19 at the side of the plunger from which it has moved, a partial vacuum, which, when the pipe 24 is exposed, draws from the carburetor, until the atmospheric or the carburetor pressure is equalized.

The chambers 20 and 21 are connected with the cylinders 6 through connecting tubes 25 and 26 respectively, these tubes being introduced through the ports 12 and 105 11 respectively.

The various oiling features in the engine herein described, are similar to those employed in the usual construction of the present day, except that the piston rod 15 is 110 oiled by means of a cup 27, into which an oil feed pipe (not shown) is introduced

from the outside of the framework of the engine. The lower edge of the cup 27 where the rod 15 passes, does not wipe the said rod, but permits the oil to pass along the surface of the same to be received in a cup 28 formed in the upper surface of the plunger 18. Small feed tubes 18^a are formed through the structure of the plunger 18 to lead into the bearings formed in the said plunger to receive a pin 29, upon which a pitman 30 is mounted, by which pitman the crank shaft 23 is driven.

Connected with the exhaust ports 10, 10, is a bifurcated extension 31 of a pipe 32. The cylinders 6 are provided with the usual form of water jacket 33, and the ordinary cooling appliances therefor.

With an engine thus described, mounted and operated singly, or as a unit of a multiple battery, the operation as far as the present invention is concerned is limited to the reciprocation of the piston rod 15 and the pitman 30. The rod is thereby thoroughly oiled, and in its extended position into the chamber 20 it carries the oil out of the box 27. Any accumulation of oil on the rod 15 gradually passes to the cup 28 on the plunger 18, and is transferred therefrom through the passages 18^a to the bearings of the pin 29 in the said plunger, lubricating the same.

Having thus described my invention, I claim as new and desire to secure by Letters Patent:

1. An internal combustion engine comprising a power cylinder; a piston adapted to be reciprocated in said power cylinder; a compression chamber formed in line with the said power cylinder and divided therefrom by a dividing wall; a compressing plunger adapted to be reciprocated in said compression chamber; a piston rod fixedly attached to said piston and to said plunger and extended through said dividing wall; a

pitman pivotally connected to said plunger and to the crank shaft of the engine; an oil cup surrounding said piston rod and supported on the said dividing wall; a cup in said plunger arranged to receive the oil from said piston rod; and percolating passages to convey the oil from said cup to the pivotal mounting of said pitman in said plunger.

2. In an internal combustion engine embodying vertically disposed rod connected pistons and a pitman pivotally connected with the lowermost of said pistons; an oiling mechanism comprising a plurality of oil receptacles disposed in superposed relation and having open communication with the side of said rod; and percolating passages leading from the lower of said receptacles to said pivotal connection between said lower piston and pitman.

3. In an internal combustion engine embodying a plurality of vertically disposed rod connected pistons and a pitman pivotally connected with the lowermost of said pistons; an oiling mechanism comprising a stationary oiling receptacle surrounding and in open communication with the sides of the rod connecting said pistons to hold the oil contained in said receptacle in direct contact with said rod; a second oil receptacle disposed below said stationary receptacle and fixedly mounted on said rod in open communication therewith to receive the oil from the sides of said rod; and percolating passages connecting said second receptacle and the pivotal connection between said lower piston and said pitman.

In testimony whereof I have signed my name to this specification in the presence of two subscribing witnesses.

CHARLES ELISHA FOGG.
